(57) **CLAIM**

An ornamental design for a cigarette mini-pack with hinged lid, as shown and described.

DESCRIPTION

FIG. 1 is a perspective view of a cigarette mini-pack with hinged lid with the lid partially open, showing our new design;

FIG. 2 is a front elevational view thereof;

FIG. 3 is a right side elevational view thereof, the left side elevational view being a mirror image duplicate;

FIG. 4 is a rear elevational view thereof;

FIG. 5 is a top plan view thereof, the bottom plan view being identical; and,

FIG. 6 is a perspective view of a cigarette pack comprising two of the mini-packs shown in FIGS. 1-5.
